UNITED STATES PATENT OFFICE.

FRANZ X. WAGNER, OF NEW YORK, N. Y., ASSIGNOR, BY MESNE ASSIGNMENTS, TO UNDERWOOD TYPEWRITER COMPANY, OF NEW YORK, N. Y., A CORPORATION OF NEW JERSEY.

TYPE-WRITING MACHINE.

SPECIFICATION forming part of Letters Patent No. 774,924, dated November 15, 1904.

Application filed November 20, 1900. Serial No. 37,095. (No model.)

To all whom it may concern:

Be it known that I, FRANZ X. WAGNER, a citizen of the United States, residing in the city, county, and State of New York, have invented 5 certain new and useful Improvements in Type-Writing Machines, of which the following is a specification.

My present invention relates to type-writing machines, and more particularly to the 10 mechanism for guiding and feeding the paper in such machines.

The object of my invention is to provide a simple and efficient mechanism whereby either 15 wide or narrow sheets may be written on with equal facility; and a further object of the invention is to provide in such mechanism a construction whereby the written portion upon the paper is presented in an unobstructed view to the operator at all times.

20 My invention consists in the novel arrangement and combination of parts, to be herein-after described and claimed.

In the accompanying drawings, wherein like 25 reference characters refer to corresponding parts in the various views, Figure I is a central sectional view of a type-writing machine, the section being taken from front to rear of the machine. This view shows sufficient number of parts of a type-writing machine to illustrate my invention. Fig. II is an enlarged 30 detail bottom view of the carriage with portions omitted and broken away. Fig. III is an enlarged detail front view of the carriage with parts broken away. Fig. IV is a detail 35 front view of one of the paper-guides. Fig. V is a side view of the same. Fig. VI is a plan view of the blank from which the main body portion of the guide is struck up. Fig. VII is an enlarged detail top view of one of 40 the paper-guides, together with the parts which coöperate therewith. In this view certain of the parts are broken away for the purpose of clearer illustration.

While I have shown in the accompanying 45 drawings one form or embodiment of my invention in connection with a front-strike type-writing machine and while the invention is particularly adapted to such machines, it should

be understood that the invention may be employed in type-writing machines of a different character.

Upon referring to Fig. I of the drawings it will be observed that the frame 1 of the machine suitably supports a pivoted type-bar 2, which is operatively connected with a slide 3, 50 that in turn is operated by a bell-crank lever 4. This bell-crank lever 4 is operatively connected to a key-lever 5, by means of which motion is transmitted to the parts to operate the type-bar. It will be understood that a 55 separate type-bar movement is employed for each type-bar, though but a single movement is shown. These type-bars, it will be further understood, are mounted in the segment and are adapted to be moved to the printing-point, 60 as indicated by the dotted line in Fig. I. The platen 6 is supported in a suitable platen-frame 7, and this platen-frame is provided with a roller 8, which bears upon a track 9, that may be moved by suitable means in a vertical direction to shift the platen in order to write upper or lower case characters. The platen-frame 7 is provided with the usual fixed paper-table 10, which guides the paper to the platen. From an examination of Fig. I of the 65 drawings it will be seen that the lower end of the paper-table terminates on a line where the main feed-rollers 11 are mounted, and so that the periphery of the feed-rollers practically forms a continuation of the paper-shelf. 70 These feed-rollers 11 may be of any suitable number and extend throughout the length of the platen. The feed-rollers are preferably 75 independently rotatable and are all mounted upon a rod 12, which is secured at its ends to 80 spring-arms 13 14 and may be held connected to these spring-arms by leaf-springs 14^x. (See Fig. I.) The spring-arms 13 14 are deflected downwardly at their ends, as indicated at 15, so that they extend into the path of the cams 90 16 and 17. These cams are carried by a suitable rod or support 18, which may be moved in a longitudinal direction, as will be herein-after more fully described. A movement of the rod or support 18 in the direction of the 95 arrow in Fig. II will cause the cams 16 and 17,

through their contact with the fingers on the arms 13 and 14, respectively, to force said arms against the tension of the spring thereof to simultaneously convey all of the main feed-rollers 11 out of contact with the platen or to a position where they are no longer effective to coöperate with the platen to feed the paper. When the main feed-rollers 11 have been moved in the manner just described to what 10 may be termed the "inoperative" position, the paper which may be contained between the platen and the feed-rollers is free to be moved by hand in any direction or to any position so far as these feed-rollers are concerned.

15 Extending from one end of the platen-frame to the other and secured against movement in the platen-frame is a rod or support 19. Upon this rod 19 is placed a plurality of sleeves 20. Each of these sleeves 20 is provided with adjusting means, such as a set-screw 21, by which the sleeve can be secured in the adjusted position, whether the adjustment be in the direction of the length of the platen or in a direction at right angles thereto. Each of these 25 sleeves 20 is provided with a spring-arm 22, which is united by a pivotal connection to a paper guide or finger 23, as indicated at 24. The spring-arm 22 has an extension 25, with which a cam 26 is adapted to coöperate. It 30 will be observed that each of the guide-fingers 23 is curved throughout at least a portion of its length to conform to the curve of the platen. Furthermore, the guide-fingers are each pivoted at or near the center thereof, so 35 that a spring-pressure may be evenly distributed throughout the length of the guide-finger. The rear ends of some of the guide-fingers are curved outwardly from the platen, as indicated in Fig. I of the drawings, and some of the guide-fingers project beyond the fixed paper-shelf 10 and are in substantial alinement with the peripheries of the main feed-rollers 11, whereas 40 others terminate near the rollers 11. (See Fig. II.) It will thus be seen that the guide-fingers 45 23 coöperate with the fixed paper-shelf 10 and the main feed-rollers 11 to receive the paper therefrom and to guide it in its movement with the cylinder. The forward end of each of the guide-fingers preferably extends to a point adjacent 50 to the printing-line. From an examination of Fig. II of the drawings it will be seen that each of the cams 26, which coöperates with a guide-finger 23, is carried upon the rod or support 18 and moves therewith.

55 These cams may be moved longitudinally upon the rod or support 18 in order that each cam may be adjusted to compensate for any adjustment of its coöperating guide-finger in the direction of the length of the platen. The 60 cams in question may each be secured in the adjusted position by a screw 27, which compresses the part which surrounds the rod 18 sufficiently to secure the cam against movement upon the rod.

65 From the foregoing description it will be

understood that a movement of the rod 18 in the direction of the arrow in Fig. II will cause the main feed-rollers 11 and all of the guide-fingers 23 to be simultaneously moved out of contact with the platen or to the inoperative 70 position.

Secured to each end of the platen-frame is a tube or bar 28, which extends toward the central portion of the platen. These tubes or bars are preferably in alinement, and each of 75 them is parallel with the platen. While there are two paper-guides 30 shown, I will describe in detail only the one shown at the right-hand end of the platen, it being understood that both guides may be constructed 80 and mounted in the same manner. Contained within the bar 28 is a support or arm 29, which may be moved within said tube in the direction of the length of the platen. The inner end of this arm 29 is secured to a paper-guide 85 30, as indicated at 31. This paper-guide 30 is preferably made resilient and extends from the support 29, which by preference is adjacent to a vertical plane extending through the axis of the platen. From the support 29 this 90 paper-guide projects toward the printing-line and extends beyond the forward ends of the guide-fingers 23, as illustrated in Fig. III of the drawings. The paper-guide 30 is curved throughout at least a portion of its length to 95 correspond to the curve of the platen, and a spring 32 coöperates with said guide to maintain it normally in contact with the platen. One end of this coiled spring 32 is secured to an end of the platen-frame, as indicated at 33, 100 whereas the opposite end of said spring bears against an extension 34 of the paper-guide. As indicated in Fig. VII of the drawings, this coiled spring 32 surrounds the so-called "bar" 28. The main body portion of the paper-guide 30 is preferably struck up from a single piece, which is first formed into a blank of the character indicated in Fig. VI of the drawings. By this construction a pair of ears 35 is provided, which constitutes a bearing for the pivot 36 of a feed-roller 37. The feed-roller 37 when secured to the paper-guide in the manner illustrated is adapted to bear upon the platen when the paper-guide is in the normal position. To the main body 105 portion of the guide is secured an independently-movable flexible arm 38, which is apertured, as indicated at 39, for the reception of the feed-roller 37. In the particular construction shown and described these feed-rollers constitute margin feed-rollers. It will 110 be observed that the guides 30 are located at portions of the circumference of the platen different from those at which the guide-fingers 23 and the feed-rollers 11 are located. It will 115 likewise be seen that these paper-guides 30 are adapted to receive the paper from the guide-fingers 23 and to direct the paper forwardly and rearwardly from the platen.

Upon reference to Fig. III of the drawings 120

it will be seen that the paper-guide 30 has a series of notches 40 in the extension 34 on the guide and that the free end of the spring 32 is provided with a finger-piece 41, by which 5 the free end of the spring can be removed from engagement in a notch 40. When the spring 32 is disengaged in the manner specified, the guide may be moved in the direction of the length of the platen, as indicated in dotted lines 10 in Fig. III of the drawings. The inward movement of the guide 30 may be limited by the head of a screw 41^x, (see Fig. VII.) which permits the guide to be readily removed when desired. While both of the paper-guides 30 have 15 been shown adjustable, I desire it to be understood that one of them need not be adjustable. In practice it has been found that it is sufficient to make the right-hand guide adjustable in the direction of the length of the platen. It will 20 be seen upon reference to the drawings that the supports for the paper-guides 30 are wholly extraneous to the printing-field. By "printing-field" I mean the space which contains the type-written matter—that is, the space between two vertical planes extending from front to rear at the limits of a written line and terminating at that line of the sheet which is 25 in the printing position. Each of the arms 29 for the guides 30 is rigidly connected to an 30 arm 43. In the present instance each arm 29 is provided with a square or angular portion 42 for this purpose and with which an arm 43 is connected. The free end of each of these 35 arms 43 extends into the path of a cam 44, carried by the rod 18, so that a movement of the rod 18 in the direction of the arrow in Fig. II of the drawings will cause the arms 29 of the paper-guides 30 to be rocked on their axes to 40 move the paper-guides out of the operative position and away from the platen. From this it will be seen that the arms 29 constitute the pivotal centers upon which the paper-guides move toward and away from the platen.

The rod 18 and the parts connected therewith are moved by a crank-arm 45, which is 45 united to an extension of said rod by a pin-and-slot connection 46. (See Figs. II and III.) This crank-arm 45 is connected to a rock-shaft 47, that is mounted in suitable bearings on the platen-frame, and has a finger-piece 48 connected thereto at its opposite end. A movement of the finger-piece 48 from the 50 initial position (shown in full lines) will cause the rock-shaft to be oscillated, and a longitudinal movement to be transmitted to the rod 18 in the direction of the arrow in Fig. II. A full movement of the finger-piece 48 will cause the various portions which coöperate with the cams 16, 17, and 44 to be brought 55 to rest on each of these cams, which is indicated in each instance by the numeral 49, so so that when the support or bar 18 is moved its full limit in the direction of the arrow in Fig. II the main feed-rollers 11, the guide-fingers 23, and the paper-guides 30 will all be

simultaneously moved away from the platen and maintained in such position until the finger-piece 48 has been again moved back to the initial position. The movement of the finger-piece 48 back to the initial position will 70 cause a reverse movement of the parts and the main feed-rollers 11, guide-fingers 23, and paper-guides 30 will again be brought into operative position.

While the paper-guides 30, the margin-rollers 37, guide-fingers 23, and the main feed-rollers 11 are all preferably spring-pressed, it should be understood that by "spring-pressed" I mean to embrace structures which are either maintained under tension by separate springs 80 or which are maintained under tension by the resiliency of the elements themselves.

From the foregoing description it will be seen that each of the guides 30 may be said to have a finger which extends partly around the 85 platen, the finger being that portion of the guide which is directly connected to arm 29.

By the use of the term "bar" or "supporting-bar" in referring to the part 28, which supports an adjustable paper-guide 30, I mean 90 to include all equivalent means for accomplishing the same purpose.

It will be observed that by the employment of the paper-guides 30 the paper is received from the guide-fingers 23 and deflected upwardly and rearwardly from the paper-platen, and that the written portion of the paper is at 95 all times maintained within sight of the operator, and that no obstruction whatever to this view is presented by the supports for the 100 paper-guides 30.

From the foregoing description it is thought that the operation of the various features of my invention will be readily understood without further reference thereto.

Having described my invention, what I claim, and desire to secure by Letters Patent, is—

1. The combination of a platen, a platen-frame, a paper-guide mounted wholly upon 110 one end of the platen-frame and means for adjusting the paper-guide longitudinally of the platen.

2. The combination of a platen, a platen-frame, separate paper-guides, independent 115 supporting means for said guides at each end of the platen-frame and means for adjusting at least one of the paper-guides relatively to the other and longitudinally of the platen.

3. The combination of a platen, a platen-frame, a spring-pressed paper-guide mounted wholly upon one end of the platen-frame and means for adjusting the paper-guide longitudinally of the platen.

4. The combination of a platen, a platen-frame, a pivotally-supported spring-pressed paper-guide mounted wholly upon one end of the platen-frame and means for adjusting the paper-guide longitudinally of the platen.

5. In a front-strike type-writing machine,

- the combination of a platen, paper-guiding mechanism for guiding the paper to the printing-point, a spring-pressed paper-guide coöperating with said platen and adapted to receive 5 the paper from the guiding mechanism, a support for said paper-guide, which support is located extraneous to the printing-field, and means for adjusting said paper-guide longitudinally of the platen.
- 10 6. In a front-strike type-writing machine, the combination of a platen, paper-guiding mechanism for guiding the paper to the printing-point and a spring-pressed paper-guide coöperating with said platen and adapted to 15 receive the paper from the guiding mechanism, a support for said paper-guide, which support is located extraneous to the printing-field and adjacent to a vertical plane extending through the axis of the platen, and means 20 for adjusting said paper-guide longitudinally of the platen.
7. In a type-writing machine, the combination of a platen, a platen-frame, a paper-guide which is adjustable in the direction of the length of the platen and a support at one end 25 of the platen-frame for said paper-guide, said guide and the support therefor terminating intermediate of the ends of said platen.
8. In a type-writing machine, the combination of a platen, a platen-frame, a paper-guide which is adjustable in the direction of the length of the platen, a support at one end of the platen-frame for said paper-guide, said guide and the support therefor terminating 35 intermediate of the ends of said platen and means for maintaining the guide in the adjusted position.
9. In a type-writing machine, the combination of a platen, a platen-frame, a spring-pressed paper-guide which is adjustable in the direction of the length of the platen and a support at one end of the platen-frame for said paper-guide, said guide and the support therefor terminating 40 intermediate of the ends of said platen.
10. In a type-writing machine, the combination of a platen, a platen-frame, a roller-bearing paper-guide which is adjustable in the direction of the length of the platen and a support 45 at one end of the platen-frame for said paper-guide, said guide and the support therefor terminating intermediate of the ends of said platen.
11. In a type-writing machine, the combination of a platen, a platen-frame, a feed-roller which is adjustable in the direction of the length of the platen, a support at one end of the platen-frame for said feed-roller, said roller and the support therefor terminating 55 intermediate of the ends of said platen.
12. In a type-writing machine, the combination of a platen, a platen-frame, a spring-pressed paper-guide provided with a feed-roller which paper-guide is adjustable in the 60 direction of the length of the platen, a sup-
- port at one end of the platen-frame for said paper-guide and feed-roller, said paper-guide and the support therefor terminating intermediate of the ends of the platen and means for maintaining the guide and feed-roller in 70 the adjusted position.
13. In a type-writing machine, the combination of a platen, a paper-shelf, a feed-roller which is independent of said paper-shelf and which is adjustable in the direction of the 75 length of the platen and a support for said feed-roller, said support being wholly extraneous to the printing-field.
14. In a type-writing machine, the combination of a platen, a paper-shelf, a paper-guide 80 carrying a feed-roller, which guide is independent of the paper-shelf and is adjustable in the direction of the length of the platen and a support for said paper-guide, said support being wholly extraneous to the printing- 85 field.
15. In a type-writing machine, the combination of a platen, a paper-guide which is adjustable in the direction of the length of the platen, a support for said paper-guide, said 90 support being wholly extraneous to the printing-field and hand-operated means for moving the paper-guide away from the platen.
16. In a type-writing machine, the combination of a platen, a spring-pressed paper-guide 95 which is adjustable in the direction of the length of the platen and is curved to conform substantially to the curve of the platen, a support for said paper-guide, said support being wholly extraneous to the printing-field and 100 hand-operated means for moving the paper-guide away from the platen.
17. In a type-writing machine, the combination of a platen, a feed-roller which is adjustable in the direction of the length of the 105 platen, a support for said feed-roller, said support being wholly extraneous to the printing-field and hand-operated means for moving the feed-roller away from the platen.
18. In a type-writing machine, the combination of a platen, a spring-pressed paper-guide carrying a feed-roller, which guide is adjustable in the direction of the length of the platen and is curved to conform substantially 110 to the curve of the platen, a support for said 115 guide, said support being wholly extraneous to the printing-field and hand-operated means for moving the paper-guide away from the platen.
19. In a type-writing machine, the combination of a platen and a plurality of independently-operating spring-pressed margin feed-rollers adjustable one with relation to another in the direction of the length of the platen, the support for said feed-rollers being wholly 120 extraneous to the printing-field.
20. In a type-writing machine, the combination of a platen and a plurality of independently-operating spring-pressed paper-guides 125 each of which carries a margin feed-roller, 130

said paper-guides being adjustable one with relation to another in the direction of the length of the platen, the support for said guides being wholly extraneous to the printing-field.

21. In a type-writing machine, the combination of a platen, a plurality of paper-guides which are adjustable one with relation to another in the direction of the length of the platen, the support for said guides being wholly extraneous to the printing-field and hand-operated means for simultaneously moving all of said paper-guides away from the platen.

22. In a type-writing machine, the combination of a platen, a plurality of independently-operating spring-pressed paper-guides which are adjustable one with relation to another in the direction of the length of the platen, supporting means for each of said guides, which supporting means are wholly extraneous to the printing-field and hand-operated means for simultaneously moving all of said guides away from the platen.

23. In a type-writing machine, the combination of a platen, a plurality of paper-guides each of which carries a feed-roller, said guides being adjustable one with relation to another in the direction of the length of the platen, a support for each of said guides, which support is wholly extraneous to the printing-field and hand-operated means for simultaneously moving all of said guides away from the platen.

24. In a type-writing machine, the combination of a platen, a plurality of margin feed-rollers which are adjustable one with relation to another in the direction of the length of the platen, a support for each of said feed-rollers, which support is wholly extraneous to the printing-field and hand-operated means for simultaneously moving all of said feed-rollers away from the platen.

25. In a type-writing machine, the combination of a platen, a fixed paper-shelf coöperating therewith, paper-feed mechanism which receives the paper from the paper-shelf, a paper-guide independent of the paper-feeding mechanism which receives the paper from said feeding mechanism, said paper-guide being adjustable in the direction of the length of the platen and hand-operated means for simultaneously moving the feeding mechanism and paper-guide away from the platen.

26. The combination of a platen, the usual paper-shelf which coöperates therewith, a plurality of curved guide-fingers which conform to the curve of the platen and contact therewith and which guide the paper to the printing-point, independent paper-guides which receive the paper from said guide-fingers and means for simultaneously moving said guide-fingers and paper-guides away from the platen.

27. The combination of a platen, a fixed pa-

per-shelf coöperating therewith, a plurality of curved guide-fingers which conform to the curve of the platen and contact therewith and which guide the paper to the printing-point, paper-guides which carry margin feed-rollers, said paper-guides being independent of the guide-fingers and adapted to receive the paper from said guide-fingers and hand-operated means for simultaneously moving said guide-fingers and paper-guides together with the margin feed-rollers out of contact with the platen without moving the carriage.

28. The combination of a platen, a plurality of curved guide-fingers which conform to the curve of the platen and contact therewith and which guide the paper to the printing-point, independently-acting paper-guides which are curved to conform to the curve of and contact with the platen and which receive the paper from said guide-fingers and hand-operated means for simultaneously moving said guide-fingers and paper-guides away from the platen.

29. In a type-writing machine, the combination of a platen, a plurality of spring-pressed guide-fingers, means for independently adjusting the tension of said guide-fingers and means for simultaneously moving said guide-fingers away from the platen.

30. In a type-writing machine, the combination of a platen, a plurality of independently-operating spring-pressed pivoted guide-fingers, means for independently adjusting the tension of said guide-fingers and means for simultaneously moving said guide-fingers away from the platen.

31. In a type-writing machine, the combination of a platen, a plurality of guide-fingers, the curve of each of which conforms substantially to the curve of the platen, spring-supports, a pivotal connection between each of said spring-supports and a guide-finger and means for simultaneously moving said guide-fingers away from the platen.

32. In a type-writing machine, the combination of a platen, a plurality of guide-fingers, spring-supports therefor, which supports are adjustable toward and away from the platen to vary the tension on the guide-fingers, a pivotal connection between each of said spring-supports and a guide-finger and means for simultaneously moving said guide-fingers away from the platen.

33. In a type-writing machine, the combination of a platen, a plurality of independently-operating guide-fingers, the curve of each of which conforms substantially to the curve of the platen, a separate spring-support for each of said fingers, said supports being adjustable toward and away from the platen and in the direction of the length of the platen and means for moving said guide-fingers away from the platen without affecting the adjustment of the spring-supports.

34. In a type-writing machine, the combina-

tion of a platen, a fixed paper-shelf which co-operates with the platen, a plurality of independent paper-guides which coöperate with the platen at different portions around the 5 surface thereof and which contact therewith circumferentially, the said guides being adjustable in the direction of the length of the platen and means for moving the guides away from the platen without affecting the adjustment thereof.

35. In a type-writing machine, the combination of a platen, a fixed paper-shelf which co-operates with the platen, a plurality of sets of independent spring-pressed paper-guides, the 15 curve of each of which conforms substantially to the curve of the platen and which coöperate with the platen at different portions around the surface thereof all of said guides being adjustable in the direction of the length 20 of the platen and means independent of the paper-shelf for simultaneously moving the guides away from the platen without affecting the adjustment thereof and without moving the carriage.

25 36. In a type-writing machine, the combination of a platen, a plurality of independent paper-guides which coöperate with the platen at different portions around the circumference thereof and which are adjustable in the 30 direction of the length of the platen, feed-rollers which are adjustable one with relation to another in the direction of the length of the platen and means for moving the guides and feed-rollers away from the platen without 35 affecting the adjustment thereof.

37. In a type-writing machine, the combination of a platen, a fixed paper-shelf, a plurality of independently-adjustable paper-guides co-operating with the platen at different portions around the surface thereof, feed-rollers carried by certain of said guides and means 40 for moving the guides away from the platen, independently of the paper-shelf.

45 38. In a type-writing machine, the combination of a platen, a plurality of independently-adjustable paper-guides coöperating with the platen at different portions of the circumference thereof, main feed-rollers which likewise coöperate with the platen and means for 50 moving the guides and main feed-rollers away from the platen.

39. In a type-writing machine, the combination of a platen, a plurality of independently-adjustable paper-guides coöperating with the 55 platen at different portions of the circumference thereof, main feed-rollers which likewise coöperate with the platen, margin feed-rollers which are independent of said main feed-rollers and means for moving the guides 60 and feed-rollers away from the platen.

40. In a type-writing machine, the combination of a platen, a paper-shelf, main feed-rollers adapted to coöperate with the platen and to receive the paper from the paper-shelf, 65 paper-guiding fingers for receiving the paper

from said feed-rollers, independent paper-guides coöperating with the platen and adapted to receive the paper from the guiding-fingers and means for simultaneously moving and maintaining the feed-rollers, guiding-fingers 70 and guides away from the platen.

41. In a type-writing machine, the combination of a platen, a plurality of paper-guides the curve of each of which corresponds substantially to the curve of the platen and each 75 of which contacts therewith substantially throughout the length of the guide, a pivotal support for each of said paper-guides and means for simultaneously turning the guides around their pivotal axes. 80

42. In a type-writing machine, the combination of a platen, a paper-guide which is adjustable in the direction of the length of the platen, a lateral support for said guide outside of the printing-field and means for readily disconnecting the guide from its support. 85

43. In a type-writing machine, the combination with a platen of a fixed bar parallel therewith and arranged above the platen and adjacent to a vertical plane passing through 90 the axis of the platen, and a device adjustably mounted upon said bar and extending forwardly therefrom directly over the platen for guiding the paper rearwardly after it has passed the printing-point. 95

44. In a type-writing machine, the combination with a cylindrical platen and a platen-frame, of a pair of devices which are adjustable one with relation to another and overhang the platen and are carried by said platen-frame, and means arranged between said devices and carried thereby for deflecting the paper rearwardly over the platen and between 100 said devices.

45. In a type-writer or the like, the combination with a platen, a platen-frame, a carrier having a stationary section extending inwardly from a point of the platen-frame beyond the platen ends, and a sliding section arranged to extend beyond the end of said stationary section and extending in the same direction, of 105 a paper-guide held to move with said sliding section and extending crosswise thereof. 110

46. In a type-writer or the like, the combination with a carrier consisting of a plurality 115 of sections adapted to fit one into the other, one of said sections being stationary, of a paper-guide connected with a movable section of the carrier.

47. In a type-writer or the like, the combination with the platen-frame, of carrier-sections secured to said frame adjacent to the platen ends and projecting toward each other, and paper-guide-carrying sections movably connected with said carrier-sections and arranged to project between the inner ends of 120 said carrier-sections. 125

48. In a type-writer or the like, the combination, with the platen-frame, of extensible carriers projecting toward each other from 130

points adjacent to the platen ends, and paper-guides connected with the inner portions of the carriers.

49. In a type-writer or the like, the combination, with the platen-frame, of alining extensible carriers located adjacent to the platen ends, and paper-guides connected with the inner portions of the carriers.

50. In a type-writer or the like, a carrier consisting of a plurality of sections extending

in the same direction, and one adapted to slide lengthwise of the other and projecting beyond the end thereof, and a paper-guide carried by a sliding section and extending transversely thereof.

FRANZ X. WAGNER.
